WILBER F. HAMMOND, JR., OF BRIDGEPORT, CONNECTICUT.

KEYHOLE-GUIDE.

1,112,133.

Specification of Letters Patent. Patented Sept. 29, 1914.

Application filed January 31, 1914. Serial No. 815,727.

To all whom it may concern:

Be it known that I, WILBER F. HAMMOND, Jr., a citizen of the United States, residing at Bridgeport, county of Fairfield, State of Connecticut, have invented an Improvement 5 in Keyhole-Guides, of which the following is a specification.

This invention relates to locks of the Yale type in which a flat or corrugated and 10 stepped key is inserted in a barrel and the barrel is rotated thereby to throw and retract the bolt, and has for its object to provide the barrels with elongated, funnel-shaped guides for the key, so that the difficulty of inserting the key in this type of 15 locks, in the dark, shall be wholly avoided.

With these and other objects in view I have devised the novel structure which I will now describe referring to the accompanying drawing forming a part of this 20 specification and using reference characters to indicate the several parts.

Figure 1 is an elevation of a lock of the Yale type, also variously known as a cylinder lock and a pin lock, having my novel key guide applied thereto; Fig. 2 a front elevation of the hub detached; Fig. 3 a side elevation of the barrel detached, showing the guide and barrel made integral; Fig. 4 25 a side elevation, and Fig. 5 a rear elevation of a key guide adapted for attachment to the barrel of a lock already in use, and Fig. 6 is an elevation of a hub and barrel of this type as ordinarily constructed, showing 30 holes drilled in the outer end of the barrel to receive the attaching pins of the key guide.

10 denotes the case of the lock proper, 11 the bolt, 12 the cylinder lock casing and 13 40 the barrel or cylinder.

The mechanism of the lock and the pin mechanism, within the casing and barrel, are not illustrated as they form no portion of the present invention.

45 The invention consists in providing the outer face of the barrel with an oblong funnel-shaped guide 14, the purpose of which is to guide the key and direct it into the key hole 15. The guide may be said to consist 50 of a mouth piece made funnel-shaped and preferably oblong, and a base having a key hole or slot registering with the key hole in the barrel of the lock. The rim of the

mouth piece is of course much longer and wider than the key of the lock and the sides 55 slope from the rim into the key hole.

In practice, I ordinarily make the sides a slightly concave curve, although this is not essential. The key guide may be formed integral with the barrel, as in Fig. 3, or 60 separate therefrom as in Figs. 4, 5 and 6. In providing new locks with my novel key guide it is preferably formed integral with the barrel. The invention is equally applicable however to locks already in use. For 65 attachment to old locks, whether in use or not, I form the key guide independent of the barrel, as in Fig. 4, and provide it on the back with two pins 16 which are preferably angular and a slot 18 for the key. Two 70 holes 17 are drilled in the face of the barrel, as clearly shown in Fig. 6, and the guide is secured in place by driving the pins into the holes. The greatest diameter of the pins, that is the diameter across corners, is 75

slightly greater than the diameter of the holes, so that the key guide is rigidly secured in place by the driving in of the pins. It is obvious that in use, no matter how 80 dark it may be, there will be no appreciable difficulty in finding the key guide and inserting the key within the rim thereof. The guide is ordinarily made oblong, its greater diameter corresponding with the height of the key slot and its sides are a slightly concave curve, or if preferred a straight incline, from the rim to the key hole, so that all that is required is to place the key, with the right edge upward, within the rim and push it forward, the inclined walls of the 85 mouth piece acting to cause it to pass without the slightest difficulty into the key hole.

Having thus described my invention I claim:—

1. In a lock of the character described, 95 the combination with a barrel having a key hole, of an oblong mouth piece surrounding the key hole and rotatable with the barrel, said mouth piece having tapering sides extending from the rim of the mouth piece 100 to the key hole.

2. In a lock of the character described, 105 the combination with a rotatable barrel having a key hole and holes in its outer face, of a key guide having a key hole corresponding with the key hole in the barrel and tapering

pins upon its back adapted to be driven into the holes in the barrel.

3. In a lock of the character described, a rotatable barrel having a key hole and having a projecting mouth piece whose sides taper from the rim to the key hole and serve as a guide in inserting the key.

In testimony whereof I affix my signature in presence of two witnesses.

WILBER F. HAMMOND, JR.
